Primary Examiner—Jeffrey Asch*Attorney, Agent, or Firm*—Skjerven, Morrill, MacPherson,
Franklin & Friel; David W. Heid; E. Eric Hoffman[57] **CLAIM**

The ornamental design for a housing for electronic components, as shown and described.

DESCRIPTION

FIG. 1 is a perspective view of a housing for electronic components showing our new design;
FIG. 2 is a top plan view thereof;
FIG. 3 is a bottom plan view thereof;
FIG. 4 is a front elevation view thereof;
FIG. 5 is a rear elevation view thereof;
FIG. 6 is a right side elevational view thereof; and,
FIG. 7 is a left side elevational view thereof.
